(57) **CLAIM**

The ornamental design for a tower for vehicle rack, as shown and described.

DESCRIPTION

FIG. 1 is a rear, top, and left side perspective view of a tower for vehicle rack showing the new design;

FIG. 2 is a front, bottom, and right side perspective view thereof;

FIG. 3 is a right side elevation view thereof;

FIG. 4 is a left side elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is a rear, top, and left side perspective view of the tower for vehicle rack and a mirror image counterpart shown in use on a vehicle; and,

FIG. 10 is a rear, top, and right left side perspective view of a pair of towers the tower for vehicle rack and a mirror image counterpart shown in use on a vehicle showing the new design.

The broken lines and environmental structure they depict form no part of the claimed design.

1 Claim, 10 Drawing Sheets
